(57) **CLAIM**

The ornamental design for a dispenser, as shown and described.

DESCRIPTION

FIG. 1 is a top, front, right perspective view of a dispenser showing a first embodiment of our new design;

FIG. 2 is a front view thereof;

FIG. 3 is a right side view thereof;

FIG. 5 is a top, front, right perspective view of a dispenser showing a second embodiment of our new design;

FIG. 6 is a front view thereof;

FIG. 7 is a right side view thereof;

FIG. 8 is a left side view thereof;

FIG. 9 is a top, front, right perspective view of a dispenser showing a third embodiment of our new design;

FIG. 10 is a front view thereof;

FIG. 11 is a right side view thereof; and,

FIG. 12 is a left side view thereof.

The broken lines in the drawings are included for the purpose of illustration and form no part of the claimed design.
